UNITED STATES PATENT OFFICE.

CHARLES F. HANSEN, OF SEATTLE, WASHINGTON.

FIRELESS COOKER.

1,320,002.

Specification of Letters Patent. Patented Oct. 28, 1919.

Application filed October 12, 1918. Serial No. 257,905.

To all whom it may concern:

Be it known that I, CHARLES F. HANSEN, a subject of the King of Norway, residing at Seattle, in the county of King and State 5 of Washington, have invented a new and useful Fireless Cooker, of which the following is a specification.

My invention relates to improvements in fireless cookers, and particularly a structure 10 that is of extremely light weight and of small cost as compared with prior devices in the art. Practically the entire structure is composed of corrugated strawboard and paper which has been impregnated with a 15 solution of waterglass, affording a non-conducting inclosure for the cooking receptacles and food, and an inexpensive and portable cooker.

I attain these objects by the devices illustrated in the accompanying drawing, in which—

Figure 1 is a vertical section of a three compartment cooker. Fig. 2, perspective of one of the plates for holding the cooking 20 receptacles in place. Fig. 3, perspective of one of the cylinders for cooking receptacles of varying diameters. Fig. 4, elevation of a two compartment cooker complete. Fig. 5 cross section of superimposed layers of 25 paper and corrugated strawboard of which the structure is composed.

Similar numerals refer to similar parts throughout the several views.

The body of the cooker 2 consists of 30 superimposed sheets of paper and corrugated strawboard, or the like, which have been previously soaked in a solution of waterglass to render the material an insulator of air and heat. These are rolled 35 to form a cylinder, the cylinder being strengthened and held in form by the metallic band 23. In this cooker the insulating material and the casing are one and the same thing, so it is important that 40 no nails or other fastenings penetrate the body of the structure. The metallic band 11 extends underneath the band 23 down one side of the body across the bottom thereof and up the other side ending under- 45 neath the band 23. This band gives additional strength to the body and affords means for attaching the handles. After 50 these bands are in place layers of the treated paper are fastened around the cylinder to 55 cover up the bands and to give the body a smooth contour. The handles 1 are then

applied. A cross section of a portion of the combined casing and insulating material as it appears in the main body of the device is shown in Fig. 5. The base of the 60 structure 12 is formed by winding several thicknesses of the prepared material around the main body, and fastening and smoothing the same by several thicknesses of the prepared paper. The bottom 26 and top of 65 the cover 25 are formed of the same material, but to give more rigidity, the corrugated board is so laid that the corrugations are transverse to each other in each successive layer. The plates represented by 70 13, 13', 14 and 15 are also made in the same way, each being provided with a lifting strap as shown at 18 and 19, Fig. 2. The sides of the cover are made in the same way 75 as the main body. The plates come in varying sizes with the device, and their use will be explained hereafter. As shown at 7, a portion of the interior of the main body is 80 cut away and on these recesses rings of sheet metal are placed to cover the exposed open spaces of the combined casing and 85 insulating material, and in addition to afford seats for the two plates 13 and 14. Fig. 3 represents a cylinder open at both ends, several of which, in different sizes, 90 are furnished with the device. They are constructed of the same material and in practically the same manner as the main body. In a fireless cooker it is desirable 95 that the insulating material be packed as closely to the cooking receptacles as possible, so these cylinders of varying size are provided to fit larger or small utensils as the cooking requires, and also to completely fill up the cooker with insulating material 100 around the sides of the utensils. The recesses 27 and 27' are to afford space for ears or projections at the upper portion of the cooking receptacles and to permit the insulating cylinder to fit closely to the cooking receptacle. Fig. 1 shows the device all 105 assembled and ready for cooking. 15 represents a plate as per Fig. 2 resting on the bottom of the cooker, 10 is a cylinder as per Fig. 3 placed directly over the plate 15, 110 within the cylinder is placed the cooking receptacle 17, over these, and resting on the recess 7 is placed the plate 14. On top of 14 is placed the plate 13'. As the cooking utensil 16 is of smaller diameter than the cooking receptacle 17, two insulating cylinders 8 and 9, are placed over the same. On

top of these is placed a plate of larger diameter, 13, which rests on the metal covered recess 7. The cooking utensil 6 placed thereon being of larger diameter than 5 16 but one insulating cylinder is required. With partially cooked and well heated food placed in the different cooking receptacles, and the cover 25 in position the apparatus 10 is ready for cooking.

10 Particular attention is called to the novel construction of this fireless cooker. The whole structure, with the exception of the annular sheet metal rings at 7, the bands 11, 15 23 and the handles 1, is made of superimposed sheets of paper and corrugated board which have been rendered non-conductive of heat and air by being treated with a solution of waterglass. It is lighter in weight, more portable and costs less money to build 20 than any other fireless cooker. The annular rings of sheet metal at 7 cover any exposed air spaces made by cutting out the recesses which afford rests for the plates which support the cooking receptacles. Any other of 25 the air spaces in the body member which might be exposed during construction are covered with the insulating material, hence the main body affords a structure filled with dead air spaces as shown in the cross section 30 5, sealed with non-conducting material. The insulating cylinders Fig. 3 are practically of the same construction as the main body. In the construction of the top, bottom and the supporting plates alternate 35 sheets of the corrugated board are laid so that the corrugations are transverse to those immediately above and below. This is done in order to give greater rigidity, the arrangement of the air spaces being approxi- 40 mately the same as is shown in the sectional view, Fig. 1. The plates are of a form to snugly fit the member with which they are adapted to be used, and the layers fastened together by suitable means. Should any 45 space exist between the top of a cooking receptacle and a supporting plate directly above, when the same are assembled, the inventor furnishes with the device pads made of the insulating material, to completely fill 50 these spaces. Or, the operator can use cloths for the same purpose. Cylinders made of the insulating material as shown at Fig. 3, being furnished in varying sizes to fit cooking receptacles that may be used, and 55 adapted to nest one within another and to snugly fit the cooker, the supporting plates, and pads all fitting snugly within the members to which they are adapted and the cover tightly fitting over all, enable the 60 user to tightly pack the cooking receptacles in insulating material, and the cooker to be tightly packed with the receptacles and insulating material. The sectional view, Fig. 1, shows a cooker with three compartments 65 for cooking, but it is evident that the de-

vice can be made with more or less compartments as desired, and still maintain the same mode of construction. Various forms of finish can be applied to the outside of the cooker to give it a pleasing appearance. 70 The inside of the cooker, the cylinders and plates to be covered with a coating of liquid asbestos.

I am aware that prior to my invention fireless cookers have been made with inclosing cases, insulating material packed therein, comprising structures that are relatively heavy, costly and not easily transported, but I do not know that any one has heretofore produced a practical, lightweight, portable 75 fireless cooker made principally of paper and corrugated board specially prepared to render the same an insulator of heat and air; a fireless cooker in which the insulating material and casing are all in one, so economical in cost and so portable that almost anyone can use it to advantage whether engaged in housekeeping or not.

The preferable form of the device is cylindrical, as the material can be easily 80 rolled into this shape, but it can be made into other forms. The solution preferred by the inventor consists of one part of commercial waterglass to six parts of water, but these proportions could be varied, or an 85 equivalent used. In fastening the parts together glue is used, but other means could be employed. It is evident that various changes in the details of construction and in the arrangements of parts can be made by 90 those skilled in the art without departing from the spirit of my invention, and therefore I do not wish to be limited to the exact disclosure, except as is required by the 95 claims.

105 I claim:

1. A lightweight fireless cooker comprising a body member and utensil inclosing members composed of corrugated strawboard alternating with sheets of paper and 110 so assembled in said members as to make a series of air cells extending longitudinally therethrough, top, bottom and utensil holding members adapted to fit within the body member, composed of sections of corrugated 115 strawboard alternating with sheets of paper and wherein each section of corrugated strawboard is laid so that the corrugations thereof lie transverse to the corrugations of the next section of corrugated strawboard, 120 all of said material having been impregnated with a solution of waterglass, means for fastening said material together, means for sealing the cells in the structure, means for strengthening the body member and applying handles thereto.

2. A device of the class described, comprising in combination, a body member of cylindrical form, a bottom member, a top member, cooking receptacle supporting mem- 130

bers adapted to fit within the body member, cooking receptacle inclosing members of cylindrical form, all made of insulating material comprising superimposed layers of paper and corrugated strawboard impregnated with a solution of waterglass, shoulder-forming annular recesses on the inner periphery of the body member, annular members adapted to fit over said recesses, seal the 5 cells therein and to afford a seat for the utensil holding members, means for sealing the cells in the structure adapted to form dead air spaces therein, means for fastening said material together, a flat metallic band 10 extending around the body member, the free ends of which are bent substantially at right angles and adapted to extend up each side of the body member and underneath said first band, said bands adapted to strengthen 15 the structure and afford means for applying 20

handles thereto, said bands and the outer periphery of said structure covered with said prepared material.

3. The combination with a fireless cooker, of detachable cooking receptacle inclosing 25 members, open at each end, composed of corrugated strawboard alternating with sheets of paper and so assembled in said members as to make a series of air cells extending longitudinally therethrough, said material having been impregnated with a solution of waterglass, oppositely disposed recesses in the interior of said members adapted to receive 30 projections of cooking receptacles, means for fastening said material together, said 35 members adapted to nest together within the cooker and serve as insulators for cooking vessels of varying sizes.

CHARLES F. HANSEN.
